UNITED STATES PATENT OFFICE.

WILFRED O. CHASE, OF REDFORD, MICHIGAN, ASSIGNEE TO STEWART-WARNER SPEEDOMETER CORPORATION, OF CHICAGO, ILLINOIS, A CORPORATION OF VIRGINIA.

VACUUM FUEL-FEEDING SYSTEM.

Application filed June 11, 1921. Serial No. 476,722.

To all whom it may concern:

Be it known that I, WILFRED O. CHASE, a citizen of the United States of America, residing at Redford, in the county of Wayne 5 and State of Michigan, have invented certain new and useful Improvements in Vacuum Fuel-Feeding Systems, of which the following is a specification, reference being had therein to the accompanying 10 drawings.

The invention relates to vacuum fuel feeding systems for use upon motor vehicles and consists in the novel construction as hereinafter set forth.

15 In the drawings:

Figure 1 is a vertical central section through the tank;

20 Figure 2 is a similar view of the upper end of the tank showing the valves in a different position of adjustment.

In the present state of the art vacuum fuel feeding systems applied to motor cars are generally provided with a vacuum tank arranged above the level of the main fuel- 25 holding tank and having two compartments, one for containing fluid which is fed directly to the carburetor and the other being connected with the main tank and alternately connected with the source of vacuum 30 and with an air vent, whereby fuel is first drawn up from the main tank into one compartment and then permitted to discharge into the other compartment. The source of vacuum in the intake manifold of the

35 engine in which, when the throttle is closed or partly closed, there is a comparatively high vacuum. This vacuum is communicated to the suction compartment of the tank, but it is obvious that the air within 40 this compartment must be drawn out and discharged into the manifold before it can be replaced by the liquid from the main tank. The air so discharged having been previously in contact with the liquid fuel

45 is carbureted, but as the proportion of the mixture is not generally right for explosion, it is obvious that the character of the mixture fed to the engine cylinders will be more or less affected thereby. This is particularly true where the engine is idling 50 and only a small quantity of carbureted air is drawn past the throttle, so that there is danger of stalling of the engine by the mixture drawn from the tank. To avoid

such a result it has been the practice in 55 the past to reduce to the minimum the volume of carbureted air drawn through the vacuum connection, but this has introduced other difficulties. Thus, where the engine is running at high speed and the 60 throttle is wide open, the vacuum in the intake is comparatively low and if this condition is long continued, there may be a failure to supply sufficient fuel for the operation of the car.

It is one of the features of the present invention to provide means for varying the area of the vacuum connection to the tank. This is so arranged that when the vacuum in the manifold is high, the engine being 70 idling or running at low speed and requiring a small quantity of fuel, the vacuum connection is restricted. This will prevent interference with proper carburetion by limiting the volume of carbureted air drawn 75 from the vacuum tank. On the other hand, when the vacuum in the manifold is low, as where the throttle is open and the engine is running at high speed and using a larger quantity of fuel, the restriction to 80 the vacuum connection is removed so that a larger area is open for the more rapid withdrawal of air from the vacuum chamber and the faster feeding of the fuel.

Another important feature of my improvement is the pneumatic operation of the valves which control the vacuum tank. This not only simplifies the construction, but renders it more sensitive and quicker in response than mechanically operated controls.

In detail, A is the vacuum tank which at its upper end is provided with an inner tank B forming the vacuum chamber and leaving an annular space C between the same and the walls of the outer tank A. D is a head for closing the tank and which is suitably chambered for the reception of the controlling valves and various connections. Within the inner tank B is a float 100 E which is fixed upon a stem F slidably engaging guide bearings G and H. The upper end of this stem carries a valve I for engaging a seat J controlling a channel K, this being connected by a nipple L to the 105 conduit leading to the intake manifold. The valve I is engaged with its seat upon the rising of the float E to a predetermined

point, thereby cutting off the vacuum connection. On the other hand, when the float lowers to a predetermined point, it will draw the stem downward, withdrawing the valve I from its seat and opening the vacuum connection. It is necessary to open and close an air vent connection to the tank B respectively upon the closing and opening of the valve I and this is pneumatically 10 operated by the following construction:

O is a gravity seated valve which controls a connection between the channel K and another channel P, which leads to a valve Q. This valve is so constructed that when the 15 channel P is in communication with the suction channel K, the valve Q will be drawn to a seat R, which seals the channel P, and said valve will also be lifted away from a seat S controlling an air vent T to the chamber in the tank B. The valve O is lifted from its seat by an upward projection U on the stem F and the arrangement is such that when the valve I is forced to its seat, the valve O will be unseated and by opening 20 the channel P to the vacuum will lift the valve Q engaging it with its seat R and withdrawing it from its seat S. This will simultaneously cut off the vacuum from the chamber B and open up an air vent thereto.

30 The chamber within the tank B has a discharge connection into the tank A, which is controlled by a check valve V', said valve automatically opening by the hydrostatic pressure of the liquid above the same and closing when vacuum within the chamber B removes such pressure. There is also provided a vent connection W between the chamber in the outer tank A and the channel W' which connects with the vent port T, so 35 that when the valve Q opens the port T, air communication is established between the chamber in the tank B and that in the tank A. X is a nipple on the head D forming an inlet connection for the liquid fuel which is 40 connected by a suitable conduit with the main fuel tank (not shown).

With the construction as thus far described, it will be understood that the dropping 50 of the float E to the predetermined low level will depress the stem F opening the valve I and connecting the vacuum with the chamber in the tank B. At such time the valve Q will be engaged with its seat S and will cut off the air vent T, so that atmospheric pressure within the chamber B can 55 be lowered to that existing within the manifold of the engine. This will lift the liquid fuel from the main tank discharging it through the nipple X into the chamber B until the rising of the float E to the predetermined point will seat the valve I. This lifting 60 of the stem will cause the upward extension U thereof to unseat the valve O, establishing vacuum connection between the nipple L and the channel P and thereby lifting

the valve Q to its seat R and withdrawing it from its seat S. Air at atmospheric pressure will thus be admitted to the chamber in the inner tank B and said chamber will also be placed in direct atmospheric communication with the outer tank A through the vent connection W. Thus the fuel which has accumulated in the upper tank B will discharge by gravity through the connection V and past the check valve V' and from the 70 lower tank it will be fed through an outlet connection Y to the carburetor.

As has been stated, one of the features of my improvement is the variable restriction in the vacuum connection corresponding to 80 variations of vacuum in the intake manifold and variations in speed or power of the engine. This is accomplished by tapering the upward extension U of the stem F so as to form thereof a metering pin for variably 85 restricting the port opening of the channel K. When the engine is idling, the high vacuum in the intake manifold will be communicated to the channel K, but the restriction caused by the metering pin U will limit the quantity of air that can be drawn through the port. This will avoid interference with the operation of the engine by introduction of too great a volume of air from 90 the vacuum tank. Under the conditions just described the metering pin is not withdrawn to enlarge the opening, for the reason that the float does not drop below its predetermined level at which the valves are reversed and suction is placed in the chamber B. 100 This is because the high vacuum in the intake manifold will, even through the restricted port, withdraw the air and fill the chamber with liquid faster than it is being withdrawn from the lower chamber in feeding to the carburetor. If, on the other hand, the throttle is open and the engine is operated at high speed, this will decrease the 105 vacuum in the manifold and greatly increase the demand for liquid fuel. Consequently, 110 the fuel will be withdrawn from the lower compartment faster than it is being supplied from the upper compartment and as the two compartments are periodically placed in communication, the level of the fluid in the 115 upper compartment will drop below its normal float level. This permits the float to correspondingly drop, thereby withdrawing the metering pin U and enlarging the port opening to the channel K. This in turn will 120 increase the volume of air that is withdrawn from the upper chamber so as to soon bring about a state of balance where the amount of liquid pumped by the tank is equal to that being fed to the carburetor.

To render this operation more certain, I 125 preferably provide means for permitting the equalization of liquids levels in the two compartments even where the vacuum is placed on the upper compartment. This consists 130

in a bleed port Z, preferably in the bottom of the compartment B and above the level of discharge through the check valve V'. The port Z is controlled by a check valve 5 Z', which is normally open, but is closed when vacuum is placed on the upper compartment by the velocity of liquid passing through the port Z. If, on the other hand, the withdrawal of the liquid fuel from the 10 lower tank is in excess of the supply from the upper compartment, the level in the lower compartment will drop below that of the check valve. Also, the low vacuum in the intake manifold will only withdraw the 15 air slowly from the upper compartment so that the force acting to close the check valve Z' is insufficient. Consequently, the bleed port Z is left open and air from the lower compartment can pass upward through the 20 liquid in the upper compartment, permitting the continued discharge from the upper to the lower compartment until either the liquid is completely withdrawn from the upper compartment or is equalized in level 25 with that of the lower compartment. This, as before stated, will withdraw the metering pin U and will thereby increase the port opening to the channel K and correspondingly increase the withdrawal of air 30 from the upper compartment and the feeding in of the liquid. Another function that is performed by the check valve Z' and port Z is to automatically permit the feeding of liquid from the upper to the lower compartment 35 whenever there is a temporary failure of vacuum in the upper compartment, due to pulsations of the engine when the throttle is wide open.

The upper level of liquid in the upper 40 compartment is determined by the vacuum in the chamber and the area of the valve O exposed to said vacuum balanced against the buoyancy of the float. It will be understood that the valve O when seated is exposed to 45 atmospheric pressure on its upper side, and therefore, to lift it from its seat, the differential between atmospheric and the vacuum pressure must be overcome. Thus when the level of liquid in the upper compartment is 50 rising, the float will be lifted until the extension U bears against the valve O, but further rise is prevented until sufficient pressure is developed to overcome the differential air pressure on the valve O. Therefore, by 55 properly proportioning the area of the valve O, any desired upper level of liquid may be established.

The mechanical construction of my improved tank is very simple and as shown in 60 detail, the various ports and passages are formed by bores in the heads D. The chamber for the valve O is closed by a cap O' which may be easily removed to obtain access to said valve. Also the seat R for the valve 65 Q is formed in a threaded cap plug Q' which

may be removed to obtain access to this valve.

What I claim as my invention is:

1. In a vacuum tank, a compartment provided with a liquid supply connection and a vacuum connection, a float in said compartment, a valve actuated by the rise of said float to cut off said vacuum connection, a second valve held to its seat by the differential pressure of the vacuum and atmospheric pressures, said second valve opposing the seating of said first valve and the rising of the float, and means pneumatically operated upon the unseating of said last-mentioned valve for opening a vent to said compartment. 75

2. In a vacuum tank, a compartment provided with a liquid supply connection, a vacuum connection and a check valve controlled liquid discharge connection, a float 85 in said compartment, a valve directly actuated by the rise of said float to cut off said vacuum connection, a valve held to its seat by differential pressure of the vacuum and atmosphere and forming a stop opposing the 90 seating of said first-mentioned valve and the rise of the float, a valve for closing an air vent to said compartment, and means for unseating said last-mentioned valve by the vacuum rendered effective on the unseating 95 of said second-mentioned valve.

3. In a vacuum tank, a compartment provided with a liquid supply connection, a vacuum connection and a check valve controlled liquid discharge passage, a float in 100 said compartment, a stem on which said float is sleeved, a valve on said stem for closing said vacuum connection, an extension of said stem beyond said valve, a valve in the path of said extension held to its seat by 105 the differential of atmospheric and vacuum pressures and opposing the closing of said first-mentioned valve and rise of said float until a predetermined liquid level is attained, a valve controlling an air vent to 110 said compartment having a portion exposed to differential pressure upon the unseating of said second-mentioned valve by which said last-mentioned valve is raised from its seat and held over until the reseating of 115 said second-mentioned valve.

4. In a vacuum tank, a compartment provided with a liquid supply connection, a vacuum connection, a check valve controlled discharge passage and an air vent port, a 120 float in said chamber, a valve directly actuated by the rising of said float to close said vacuum connection, a valve for closing said air vent, and means actuated by the differential of atmospheric and vacuum pressure 125 for controlling the alternate seating and unseating of the last mentioned valve.

5. In a vacuum tank, a compartment provided with a liquid supply connection, a check valve controlled liquid discharge pas- 130

sage and a valve controlled air vent, of a float in said compartment, a valve directly actuated by the rise of said float for cutting off said vacuum connection, and means subjected to differential pressure in the atmosphere and the vacuum for resisting the rise of said float and closing of said vacuum valve, and means pneumatically operated on the overcoming of said resistance for unseating said air vent valve.

6. In a vacuum tank, an upper compartment and a lower compartment, the upper compartment being provided with a liquid supply connection, a vacuum connection, a valve-controlled vent connection and a check valve controlled liquid discharge, a float in said upper compartment, a valve actuating said float for opening and closing said vacuum connection, pneumatically operated means controlled by said float for operating said air vent valve and a vent connection between the upper and lower compartment, a normally open valve controlling said vent adapted to be closed by the vacuum and automatically opening on failure of vacuum.

7. In a vacuum tank, a compartment provided with a liquid supply connection, a

vacuum connection, a discharge passage and an air vent port, of a float in said compartment, a valve actuated by said float to close said vacuum connection, a valve for closing said air vent, a connection between said vacuum connection and said air vent port, a gravity seated valve in the last mentioned connection, and means for unseating said gravity seated valve simultaneously with the seating of the first mentioned valve thereby causing the second mentioned valve to become unseated.

8. In a vacuum tank, an upper compartment and a lower compartment, the upper compartment being provided with a liquid supply connection, a vacuum connection, a valve-controlled vent connection, and a check valve controlled liquid discharge, a float in said upper compartment, a valve actuated by said float for opening and closing said vacuum connection, pneumatically operated means controlled by said float for operating said air vent valve, and means for permitting the equalization of liquid levels in the two compartments.

In testimony whereof I affix my signature.

WILFRED O. CHASE.
